Application December 1, 1950, Serial No. 198,642

5 Claims. (Cl. 312—289)

1

My invention pertains to furniture and more specifically to an article of furniture, designed and constructed to achieve the dual function of a folding display booth and a transporting chest.

My invention is planned for use by a commercial exhibitor at an industrial convention or the like as the solution for a low cost, limited space, and secondary display of merchandise. The folding display booth requires neither skilled labor, special tools, nor excess time to assemble. During the exhibition there is no problem of shipping container, storage or disposal. Again, after use of the booth is terminated the job of repacking is achieved simply and quickly, with a minimum of effort.

The device of my invention provides a center section comprising an illuminated canopy and display and storage pedestal maintained in a spaced relation by an intervening rear wall, two hinged side wings adjacent the center section, each with an additional hinged outer wing extension, and two oblique braces or headers hinged and pivoting conveniently at the hinged side wings and locked into an adjacent side wall of the illuminated canopy of the center section.

Now it is an object of my invention to assemble the above mentioned elements of uniform height and width in a folding structure which is intended to be arranged in an upright position when used as a display booth and which is capable of folding in such a way, due to its novel construction, as to form a transporting chest.

My invention further contemplates the use of oblique braces to interconnect and maintain in rigid spaced relation the hinged side wing and illuminated canopy of the center section.

It is a further object of my invention to transmit light from within said oblique brace through a translucent plastic sidewall as auxiliary display lighting for the hinged side wing or through a translucent plastic bottom wall to furnish supplementary display booth illumination.

A further object of my invention is the novel use of a pivoting hinge on one end of the oblique brace to affix said brace to the top of either the inner face of the hinged side wing or the adjacent side wall of the illuminated canopy of center section.

Another object of my invention is a novel locking arrangement for affixing the unhinged unpivoted end of said oblique brace to the top of either the inner face of the hinged side wing or adjacent side wall of the illuminated canopy of the center section.

It is a further object of my invention to pro-

2

vide a hinged door in the illuminated side wall of the oblique brace or illuminated canopy, thus exposing said fixtures for service.

A further feature of my invention is an extending top side wall of the illuminated canopy and an extending bottom side wall of the pedestal projecting beyond the side walls of said canopy and pedestal the thickness of the side wings and outer wing extensions, thereby locking the center section and side wings and outer wing extensions together when the display booth is folded together for shipment.

An additional feature of my invention contemplates complementary grooves cut in the vertical frontal face of the display and storage pedestal in the center section to fit the oblique brace when said brace is folded into position for transporting.

A further feature of my invention is the use of oblique intervening rods, supporting the forward portion of the illuminated canopy of the center section in spaced relationship from the forward portion of the upper face of the display and storage pedestal of the center section.

My invention has other features and objects which will be more fully described in the explanatory discussion of the accompanying drawings and which will be more particularly indicated in and by the appended claims.

Referring to the accompanying drawings in which like numerals of reference indicate similar parts throughout the several views:

Fig. 1 is a perspective front view of the folding display booth in an upright position and with hinged side wings and additional hinged outer wing extensions and oblique braces assembled in position for use;

Fig. 2 is a perspective front view of the folding display booth ready for shipment with the hinged side wings and hinged outer wing extensions folded about the center section and with said hinged outer wing extensions locked together with appropriate hasps and locks;

Fig. 3 is a perspective front view of the folding display booth showing the same partially unfolded;

Fig. 4 is a top elevation of the folding display booth assembled for use;

Fig. 5 is a sectional top elevation, with parts broken away, of a hinged side wing and hinged outer wing extension, oblique brace and canopy of the center section, showing the mounting at both ends of the oblique brace;

Fig. 6 is a sectional view on line VI—VI of Fig. 5;

Fig. 7 is an end view of the locking end of the oblique brace on line VII—VII of Fig. 6;

Fig. 8 is a perspective end view of the locking end of oblique brace and canopy of the center section, showing an alternative guide and locking arrangement for affixing said oblique brace to said canopy;

Fig. 9 is a sectional view of the locking end of the oblique brace and canopy of the center section, as on line IX—IX of Fig. 8;

Fig. 10 is a sectional view on line X—X of Fig. 9; and

Fig. 11 is a sectional view similar to Fig. 9, but showing the brace and canopy locked together.

In the specific embodiment of the invention illustrated in said drawings, and orienting the several parts in their relationships as shown assembled for display use in Fig. 1, the device may be considered as constructed about a center section 1. This center section is shown as consisting of a box-shaped illuminated canopy 2 and a box-shaped storage and display pedestal 3, said canopy 2 and pedestal 3, having the same length and width and being connected together and held in a spaced relation at their respective rear portions by a center section display wall 4. The bottom or under wall 5 of canopy 2 is conveniently connected to and supported in parallel relation to the top 6 of pedestal 3 by oblique supporting rods 7 conveniently cylindrical in shape and located at the forward ends of canopy and pedestal.

Said illuminated canopy 2 is a hollow closed six sided box having rectangular shaped sides adjacent ones whereof are in perpendicularity. The front wall 8 of said canopy may be suitably hinged at the top to the front end of the canopy top wall 9. Said front wall 8 of canopy 2 contains a translucent section 10 of glass or plastic or other material and of desired shape and decoration for advertising and illuminating purposes. Said top wall 9 of canopy 2 extends beyond the side walls and front and rear walls of said canopy 2, a distance equal to the thickness of wing 16 and wing extension 17 hereinafter described. Illumination for a display on the pedestal top may be supplied from the canopy in suitable manner such as by an appropriate spotlight 12 supported at the underside of under wall 5 of the canopy, capable of directional adjustment for illuminating either or both the center section display wall 4 and top wall 6 of pedestal 3.

Said pedestal 3 is also a box-like structure which may be closed and hollow and having parallel rectangular shaped side walls perpendicular to top 6 and rear wall 4. The front sidewall 13 of said pedestal 3 has vertical grooves 14 of right angle predetermined cross section cut in the corners. Said grooves 14 are used in folding the display booth for transporting. Bottom side wall 15 of pedestal 3 is rectangular in shape and projects beyond the side walls and front and rear wall of said pedestal 2, a distance equal to the thickness of center section display wall 4.

Center section display wall 4, having the same width as canopy 2 and pedestal 3 and a height extending from the underside of top wall 9 of canopy 2 to the top side of bottom wall 15 of pedestal 3, contacts and supports both canopy 2 and pedestal 3 along the entire area of their respective rear walls. Said center section display wall 4 is suitably hinged along each vertical side to a side wing 16 thereat. Each said side wing 16 is rectangular in cross section and has

a height and thickness the same as display wall 4 and a width equal to the length of canopy 2 and pedestal 3. In open condition of the display as shown in Figs. 1 and 4, said side wings 16 extend laterally in the same vertical plane as said display wall 4, and are in turn each conveniently hinged along their outer vertical sides to outer wing extensions 17. Said outer wing extensions 17, stretching out in use in the same plane as sidewings 16 and display wall 4, are rectangular in cross section and have a height and thickness the same as side wings 16 and width equal to one-half the width of canopy 2 and pedestal 3.

The side walls of canopy 2 and pedestal 3 are suitably plywood. Center display walls 4, side wings 16 and outer wing extensions 17 are also conveniently plywood, reinforced with suitable wood members, such as a peripheral frame cross braced with appropriate, perpendicular and intersecting wood slats dividing the exterior face of said display wall 4, side wings 16 and outer wing extensions 17 into rectangular sub areas.

With the booth set up for use, there are provided two horizontally disposed oblique braces 18, having the same height as side wall 19 of canopy 2, in assembled position therewith. One end of each said brace is affixed by a pivoting hinge to the upper, outer corner of side wings 16 and the other end is secured by a novel locking device 30 to the forward end of side wall 19 of canopy 2. Said braces 18 are basically hollow six sided boxes having rectangular plywood walls. Both end walls 23 of the brace are beveled to fit flush, when the folding display booth is assembled, one 35 against outer wing 16 and the other against a forward part of the side wall 19 of canopy 2. The abutting edges of oblique braces 18, side wings 16, and side wall 19 of canopy 2 conveniently coincide for improved appearance and 40 bracing purposes. The front wall 20 of each brace 18 may be, if desired, suitably hinged at its top edge to the front edge of top wall 21 of its respective brace 18 for servicing lamps therein. Said front wall of each brace is shown with 45 a window opening closed by a glass, plastic or other translucent section 22 for advertising and illumination purposes.

Referring to the beveled end walls 23 of oblique braces 18, it will be understood that the pivoting hinge 24 may be affixed at either one of the end walls 23 and the novel locking device contained in the other end wall 23. Said pivoting hinge 24, shown in detail in Figs. 5 and 6 suitably attached to side wing 16, consists of a strap hinge 25 and 50 a pivoting arm 26. Said strap hinge 25, in direction of its hinge pin, has a length conveniently equal to the height of brace 18, and is affixed flush to the inner edge of said end wall 23 by a plurality of bolts 27 conveniently equally spaced apart along a line parallel to the hinge pin. Said bolts project through end wall 23 and are threaded thereto to suitably secure the side plate or leaf of strap hinge 25 to the end wall 23 with aid of washers 28 and nuts 29. The other side 55 plate or leaf of strap hinge 25 is attached along its lower portion to pivoting arm 26 by three screws 30 which are cut off flush with the outer face of arm 26. Said pivoting arm 26 is here shown as a flat metal plate of right triangular cross section. The edges of arm 26 forming the right angle are coincident with the inner and bottom edge of the side plate of hinge 25 to which it is secured. At the outer acute angle vertex of arm 26, said arm is attached pivotally to side 60 wing 16, by a bolt 31, washer 32, and nut 33.

The complementary bolt hole in arm 26 is enlarged to receive a hollow cylindrical fiber bushing 34 which allows arm 26 to pivot freely when it is desired. A circular fiber washer 35 secured by bolt 31 between the juxtaposed surfaces of outer wing 16 and arm 26 reduces friction and aids the pivoting movement of said arm.

A preferred form of novel locking device for securing the other end wall 23 of oblique brace 18, in this instance the forward end of the brace 18, to side wall 19 of canopy 2, is shown in detail in Figs. 5, 6 and 7. The portion of said novel locking arrangement in end wall 23 consists of two cylindrical metal guide pins 35 conveniently spaced along the vertical center line of end wall 23 and a locking pin keyway 36 of appropriate width. Each guide pin 35 is affixed on the inner surface of end wall 23, through agency of a rectangular guide-pin plate 38 to which said guide-pin is riveted as at 39. The guide-pin plates 38 are suitably attached to the inner surface of end wall 23 by four screws 40. Said guide pins 35 project through said end wall 23 and therebeyond a distance conveniently greater than the thickness of side wall 19 of canopy 2. Aforementioned keyway 36 is cut through the end wall 23 according to the present showing backwards from about the juncture of the vertical and horizontal center lines of said end wall 23 along said horizontal center line and into the rear wall 37 of said brace 18. The portion of keyhole slot 36 in end wall 23 is rectangular in cross section and has just sufficient width to admit a pivoted locking rod 41, whereas the portion of slot 36 cut into rear side wall 37 of brace 18 is enlarged or circular in cross section of sufficient diameter to admit locking rod wing nut or the like 42.

Referring now to that portion of the novel locking device in side wall 19 of canopy 2, two metal canopy guide pin plates 43, rectangular in shape are affixed to the outer surface of the forward end of side wall 19 by convenient screws. Each guide pin plate 43 has a guide pin hole 44 suitably centered in said plate 43 of sufficient diameter to admit guide pin 35 with a small amount of clearance. The guide pin holes 44 are continued through side wall 19 of canopy 2. Said canopy guide pin plates 43 are vertically centered along a line parallel to the forward vertical edge of side wall 19 of canopy 2 so that the abutting vertical front edges of front side wall 20 of brace 18 and side wall 19 of canopy 2 coincide for improved appearance. Centered horizontally about the intersection of the vertical center line of canopy guide pin plates 43 and the horizontal center line of side wall 19 of canopy 2 (said horizontal center line being in the same horizontal plane as the horizontal center line of end section 23 of brace 18) is a pivoting locking rod 41. Said locking rod 41 is preferably a cylindrical rod of convenient length, having a transverse pivoting head 46 and brazed at one end thereof and threaded toward its other end for receiving wing nut 42, said threaded end preferably terminating as a stop 47 by being headed or upset and thereby preventing removal and loss of the wing nut.

Said pivoting head 46 is a hollow cylinder receiving a pivot pin 48 therethrough for enabling the locking rod to be swung laterally in a plane perpendicular to the center line of locking rod 41. Said pin 48 projects at the ends of said head into suitable holes in mounting brackets 49 therefore embedded in the side wall of said canopy. Said brackets 49 are affixed to side wall 19 of canopy 2 by bolts 50 which project through said wall and through an inner retaining plate 51 for receiving suitable nuts 52.

At one side of pivoting head 46, the side wall 19 of the canopy preferably provides a pocket 45 of appropriate size and shape for the locking rod to swing into when not in use and to be out of the way when the wing 16 is swung into juxtaposed or closed position to the said canopy. Said canopy locking rod pocket 45 is rectangular in cross section and is deep enough and long enough in a direction longitudinally of the canopy from the vertical center line of locking rod 41 to exceed the combined lengths of said locking rod 41 and stop 47, and is of appropriate width and depth to receive said locking rod and wing nut entirely therein.

An alternative novel locking device is shown in Figs. 8 to 11. Referring to the end side wall 23 of brace 18 of this modified showing, inner guide pin plates 38 are affixed by screws to the inner surface of end side wall 23 aligned as explained above with the guide pins 35 projecting through suitable holes in sidewall 23 as aforementioned. Concentrically at the projecting end of lower guide pin 35 is locking head 53 with a diameter equal to that of the guide pin 35 and a short unthreaded shank with a diameter less than that of the guide pin 35 so as to provide an undercut shoulder for the head.

Referring to the side wall 19 of canopy 2, canopy guide pin plates 43 with guide pin holes 44 are affixed to the outer surface of side wall 19 by screws and aligned as mentioned above. Said holes 44 are continued through side wall 19. Secured by upper screw 54 to the inner surface of side wall 19 and extending from the continuation of upper guide pin holes 44 in side wall 19 to the bottom wall 5 of canopy 2 is a keeper spacing plate 55 suitably rectangular in cross section. The width of plate 55 is so selected that when bottom guide pin 35 continues through guide pin hole 44 and its continuation holes through side wall 19 and keeper spacing plate 55, the outer end of guide pin 35 below the head is flush with the outer surface of said plate 55 and the head and neck of said guide pin project outwardly beyond the said plate. Held on the outer surface of plate 55 by screws 54, with freedom to slide is keeper 56, a rectangularly shaped flat plate which has a slot the margin whereof underlies head 53 of pin 35. The upper end of keeper 56 extends beyond the upper end of spacing plate 55 and has a small right angle lip 62 to which is attached a suitable recovery spring 57, secured in parallel alignment with keeper 56 at the top of the inner surface of side wall 19 of canopy 2 by screws 58 and hollow spacing bushing 59. The lower end of keeper 56 projects beyond the lower face of said plate 55 and through a keeper slot 60, cut in the bottom wall 5 and side wall 19, of canopy 2. The lower end of said plate 55 conveniently bends forward 90° to form a lower lip 61. Said lip 61 is shown extending parallel to and in the same direction from the body of keeper 56 as upper lip 62. The outer edge of lower lip 62 is furthermore shown flush with the outer surface of side wall 19 of canopy 2. Said keeper slot 60 has the same rectangular cross section as lower lip 61 and is cut to a depth adequate to provide storage space for lower lip 61 during transporting. The depth of the front portion of slot 60 cut in the side wall 19 of canopy 2 is increased to conveniently admit a human finger 75 for securing lowering engagement with the lip

of keeper 56. When lip 61 rests in slot 60, the shanks of retaining screws 54 rest against the top margins of slots 63 cut through keeper 56 along the vertical center line thereof. Said slots 63 have a width slightly greater than diameter of the shank of screw 54. Furthermore, with lower lip 61 of keeper 56 resting in groove 60, the upper circular portion of locking bolt keyhole slot 64 coincides with the continuation holes of guide pin hole 44 through the side wall 19 of canopy 2 and keeper spacer plate 55. The lower slotted portion of keyhole slot 64 continues downward along the vertical center line of the slots 63. The length of slots 63 and the length of the lower slotted portion of keyhole slot 64 are suitably the same as the distance which upper lip 62 of keeper 56 projects above the top surface of keeper spacing plate 55 in this recovered position of keeper 56. Pulling the keeper down to its lowermost position will register the enlargement of the keyhole slot with the headed pin 54 and thereby permit withdrawal of the head therethrough. All members 53 through 64 are metal, such as stainless steel.

Illumination for the translucent section 22 of front side wall 20 of brace 18 or any other side wall of brace 18 requiring illumination is supplied by lamps or a light bulb such as fluorescent lamp 65 (see Fig. 4). After locking oblique brace 18 to side wall 19 of canopy 2 by either of the above mentioned methods, extension plug 66 for light 65 is inserted in a complementary receptacle 67 conveniently positioned on the outer surface of side wall 19. Illumination for the translucent section 10 of front side wall 8 of canopy 2 is supplied conveniently by suitable lamps, such as fluorescent lamp 68. Said lamp 68, connected in parallel with lamps 65, are conveniently connected by a suitable extension cord and male plug 69 to a nearby 115 volt, alternating current house line.

To disassemble and fold the device of my invention to form its own transporting chest, first extension cord and plug 69 and extension plug 66 are disconnected. Considering the preferred embodiment of the novel locking device of two guide pins 35 and pivoting locking rod 41 each oblique brace 18 is unlocked from canopy 2 in the following manner: Front side wall 20 of oblique brace 18 is raised and locking wing nut 42 is backed off from the inner surface of end wall 23 of said brace 18. Both locking rod 41 and juxtaposed wing nut 42 are pushed by hand through locking pin keyhole slot 36 in end wall 23 and sidewall 37 of said brace and into canopy locking rod pocket 45. Side wing 16 is swung backward, thereby removing the two guide pins 35 of the brace 18 from guide pin holes 44 in sidewall 19 of canopy 2. This allows oblique brace 18 to swing on strap hinge 25 against the inner surface of said wing 16 and then pivot down on pivoting arm 26 along said inner surface of sidewing 16. At the end of this pivoting motion said brace 18 and pivoting arm 26 reach a vertical position perpendicular to the floor and the bottom edge of front side wall 20 is parallel to the outer vertical edge of side wing 16, as shown in Fig. 3. Side wings 16 and juxtaposed oblique brace 18 are folded against the side walls of center section 1, thereby securing oblique braces 18 in their respective complementary vertical grooves 14 cut in the corners of front side wall 13 of pedestal 3. In turn outer wing extensions 17 are folded against the front wall of center section 1, thereby immobilizing oblique

braces 18 in their complementary grooves 14. The closed outer wing extensions then form a front closure for the folded structure and are locked with suitable hasps and locks. Top wall 9 of canopy 2 and bottom wall 15 of pedestal 3 fit flush with the outer faces of side wings 16 and outer wing extension 17 thereby interengaging with said side wings 16 and outer wing extensions 17 for constituting a secure box or crate during shipment.

Considering now the alternative locking device consisting of top guide pin 35 and bottom guide pin 35 and locking bolt 53 in end wall 23 of oblique brace 18, and keeper 56 in side wall 19 of canopy 2, each oblique brace 18 is unlocked from canopy 2 in the following manner: A suitable finger is inserted into the undercut portion of keeper slot 60 in side wall 19 of canopy 2 and lower lip 61 of keeper 56 is pulled down as far as possible. With keeper 56 in this position, the upper circular portion of locking bolt keyhole 64 is aligned concentrically with guide pin hole 44 in canopy guide pin plate 43 on the outer surface of side wall 19, and the continuation holes through side wall 19 and keeper spacer plate 55. If side wing 16 is swung backward, lower guide pin 35 and locking bolt 53 can be withdrawn from keeper 56 and both guide pins slid from their respective holes in said side wall 19, thereby allowing the oblique brace to swing inward to outer wing 16 and downward along outer wing 16 as explained above. The above mentioned operation of folding and locking the side wings 16 and outer wing extension 17 against center section 1 is then repeated and the display booth has become its own transporting chest or crate.

It will now be clear from the foregoing description of the device of my invention that I have devised a combined folding display booth and transporting chest with several novel features. Due to the uniform height and width of side wings 16, outer wing extensions 17 and center section 1, said device is capable of arrangement in an upright position when used as a display booth and is capable of folding around said center section 1 as to form its own transporting chest. Further, when assembled as a display booth, oblique braces 18 interconnect and maintain in rigid spaced relation hinged side wings 16 and illuminated canopy 2 of center section 1. A further feature of my device is the transmission of light through the translucent section 10 of front side wall 8 of canopy 2 and through the translucent section 22 of front side walls 20 of oblique braces 18 for advertising purposes or the transmission of light through similar translucent sections in any other appropriate side wall of either canopy 2 or oblique braces 18 for auxiliary display lighting for hinged side wings 16 and center section display wall 4. The use of pivoting hinge 24, consisting of strap hinge 25 and pivoting arm 26 to affix one end wall 23 of oblique brace 18 to either the inner face of hinged side wing 16 or the forward portion of sidewall 19 of canopy 2 is a novel achievement.

An added characteristic of my invention is the unusual locking device for securing end side wall 23 of oblique brace 18, to, say, side wall 19 of canopy 2 for convenience of summation. In the preferred embodiment two guide pins 35 projecting from end side wall 23 of brace 18 engage canopy guide pin holes 44, aligning said brace 18 with canopy 2. Pivoting locking rod 41 slides out of canopy locking rod pocket 45 through locking rod keyhole slot 36

in end wall 23 of brace 18 and is secured against the inner surface of said end wall 23 by tightening locking rod wing nut 42.

In the alternate embodiment of said locking device lower lip 61 of keeper 56 (inside canopy 2) is pulled down by finger aligning upper circular end of locking bolt keyway 64 with lower guide pin holes 44 and its continuation holes through side wall 19 of canopy 2 and keeper spacer plate 55. Upper guide pin 35 and lower guide pin 35 and locking bolt 53 projecting from end wall 23 of brace 18 are inserted into their respective guide pin holes 43 and continuations thereof. Lower lip 61 is released and recovery spring 57 pulls keeper 56 upward thereby locking under the head of locking bolt 53 in the lower slotted portion of locking bolt keyhole slot 64.

An added feature of my device is the hinging of front wall 8 of canopy 2 and front wall 20 of oblique braces 18, at the top from their respective top side walls to facilitate servicing lights 65 and 68 and the novel locking devices mentioned above.

An unusual principal part of my invention is the extended top side wall 9 of canopy 2 and extended bottom side wall 15 of pedestal 3. When said device is folded about center section 1 to form its own transporting chest, said walls 9 and 15 immobilize side wings 16 and outer wing extensions 17 during shipment.

A further feature is the vertical grooves 14 cut in the corners of the front and side walls of pedestal 3, said grooves having a horizontal cross section complementary to oblique brace 18. When said braces 18 are juxtaposed in grooves 14 for shipment, outer wing extensions 17 folded against front wall of center section 1 prevent any motion of said braces 18 in transit.

A supplementary characteristic is the use of oblique rods 7 supporting the forward portion of bottom sidewall 5 of canopy 2 in parallel spaced relation to the top side wall of pedestal 3.

It is believed that the novel features of the device of my invention will be fully understood and while I have herein shown and described said features in detail, I do not wish to be limited thereto except for such limitations as the claims may impart.

I claim:

1. A combined folding display booth and transporting chest comprising a back wall, two sides hinged to the side edges of the back wall, and front wall sections hinged respectively to outer edges of the said two sides, a fixed canopy projecting from the top part of the back wall and also constituting a top for the folded chest, said canopy having vertical walls depending below the level of the top of said side walls, and headers mounted to extend diagonally between said vertical side walls of the canopy and side walls in open position of the booth and hinged to hang vertically in closed position of the chest.

2. A combined folding display booth and transporting chest comprising a pedestal and a canopy above the pedestal and spaced therefrom, a back

wall secured to and holding both said pedestal and canopy in fixed relation to each other, said canopy having vertical walls depending below the level of the top of said side walls, side walls hinged to the back wall, and headers hinged to said side walls and having releasable attachment to said vertical side walls of the canopy in display booth position.

3. A combined folding display booth and transporting chest comprising a back wall, two sides hinged to the side edges of the back wall, and front wall sections hinged respectively to outer edges of the said two sides, and a fixed canopy projecting from the top part of the back wall and also constituting a top for the folded chest, headers mounted to extend diagonally between said canopy and side walls in open position of the booth and hinged to hang vertically in closed position of the chest, and a pedestal at the bottom of said back wall beneath said canopy and having grooves for reception of the vertically hanging headers in closed position of the chest.

4. A folding display booth comprising a back wall, two side walls hinged to the back wall and adapted to extend laterally therefrom at opposite sides thereof, a canopy projecting forwardly from said back wall, said canopy having vertical walls depending below the level of the top of said side walls, headers each having pivotal mounting to the said side walls and also hinged to swing forwardly away from the side wall, and an interlocking releasable connection between forward end portions of the said headers and vertical side walls of the canopy.

5. A combined folding display booth and transporting chest comprising a pedestal and a canopy above the pedestal and spaced therefrom, a back wall secured to and holding both said pedestal and canopy in fixed relation to each other, side walls hinged to the back wall, said canopy having vertical walls depending below the level of the top of said side walls, headers having height substantially the height of said vertical walls of the canopy, and pivots for and next the under edges of the headers and below the level of the vertical walls of the canopy for locating the headers in opposition to the said vertical walls in open position of the booth and entirely below the canopy in closed position of the booth.

RALPH L. WINTERSTEEN.
